ATTORNEY

UNITED STATES PATENT OFFICE.

JULIUS P. BARNETT, OF DONNELLSON, IOWA.

CIGARETTE-LIFTER.

1,241,463.

Specification of Letters Patent. Patented Sept. 25, 1917.

Application filed December 22, 1916. Serial No. 138,432.

To all whom it may concern:

Be it known that I, JULIUS P. BARNETT, a citizen of the United States, residing at Donnellson, in the county of Lee and State of Iowa, have invented new and useful Improvements in Cigarette-Lifters, of which the following is a specification.

This invention relates to cigarette lifters and it consists in the novel features herein-
10 after described and claimed.

An object of the invention is to provide a lifter of simple and durable form adapted to be used in a carton or package which contains the cigarettes and which may be readily used for lifting the cigarettes from the carton or package whereby the ends direct may be raised above the head and consequently the cigarettes may be easily grasped and removed from the carton or package.

20 With this object in view the device includes strips of relatively heavy paper having intermediate portions which lie in close proximity to each other. The lower end portions of the said strips are bent approxi-
25 mately at right angles to the intermediate portions thereof and secured to a strip which traverses the full length of the said end portion and is adapted to lie in the bottom portion of the carton or package. The upper
30 end portions of the first mentioned strips are adapted to be bent at right angles and lie over the upper ends of the cigarettes when the carton is closed and the last mentioned bent ends of the strips may be straightened
35 out and used as handles for raising the strips and the cigarettes when it is desired to remove the same from the carton or package.

In the accompanying drawing,

Figure 1 is a vertical sectional view of a
40 carton or package showing the cigarette lifter applied.

Fig. 2 is a perspective view of the same;

Fig. 3 is a perspective view of strips used in the parts.

45 As illustrated in the accompanying drawing the carton or package 1 is made of the usual form adapted to hold the cigarettes as indicated at 2. The said carton is provided at its upper edge with a flap 3 adapted to be folded over the upper ends of the cigarettes and secured in a usual manner.

The cigarette lifter comprises strips 4 of

relatively heavy paper having their intermediate portions lying in close proximity to each other and extending between the inner-
55 most cigarettes and the bunch or collection of cigarettes in the carton 1. The said strips are provided at their lower ends with angularly disposed extremities 5 which extend along and are secured to the upper surface
60 of a strip 6 which serves as means for holding the said extremities 5 at their angular disposition with relation to the intermediate portion of the strips 4. The strips 4 are further provided at their upper ends with
65 extremities 7 which may be bent down over the upper ends of the cigarettes 2 as shown in Fig. 1 and thus the said extremities 7 may serve as additional means for protecting the
70 upper ends of the cigarettes.

When it is desired to use the lifter for the purpose of raising the cigarettes in the carton or package the flap 3 is folded back from over the extremities 7 and then the said extremities 7 are straightened up approximately in alinement with the intermediate portions of the strips 4 and an upward pull is exerted through the extremities 7 upon the strips 4 the said strips are raised in the carton or package 1 and the upper ends of the
80 cigarettes 2 are lifted above the upper edge of the said carton or package. Thus it will be seen that a simple and efficient means is provided for raising cigarettes in a carton or package and that the said means serve an
85 additional function of protecting means for the end portions of the cigarettes when the same are contained within the carton or package.

Having described the invention what is
90 claimed is:—

In combination with a carton, a lifter comprising strips having intermediate portions in close proximity to each other and provided at their lower ends with angularly disposed extremities and a third strip secured to the lower surfaces of the said extremities and traversing the length thereof and serving to hold the intermediate portions of the first mentioned strips at right
95 angles to their lower extremities.

100 In testimony whereof I affix my signature.

JULIUS P. BARNETT.
